UNITED STATES PATENT OFFICE.

PETER G. ROUSSEAS, OF BROOKLYN, NEW YORK.

COFFEE URN AND BIGGIN.

Application filed July 28, 1927. Serial No. 209,037.

This invention relates to a coffee urn and biggin therefor which is suspended in the urn and is constructed of textile material with a substantially flat bottom whereby the 5 ground coffee is distributed over a wide area and hot water is sprayed toward the bottom.

An object of the invention is to provide a nozzle arranged above the biggin so that it will not materially interfere with the removal of the biggin and the water issuing 10 from the mouth of the nozzle is directed downward at an angle to one side of the biggin and parallel with the other side thereby striking the entire bottom to thoroughly 15 intermingle with the ground coffee.

Another object of the invention is to provide a pocket having a removable resilient wire member arranged to shape the bottom and keep it tensioned centrifugally so that it 20 will not sag and the coffee grounds will scatter about the bottom.

The invention resides more particularly in the novel combinations hereinafter described and claimed, reference being made 25 to the accompanying drawing in which:

Fig. 1 represents a vertical section of an urn embodying this invention.

Fig. 2 is an inverted plan view of the biggin.

30 In the drawing the numeral 5 designates a boiler having a cover 6 and a hot water inlet pipe 7 leading into the upper part of the boiler as is well known. The inlet pipe is equipped with a perforated nozzle 8 the 35 outlet or apex of which forms a right angle as indicated in Fig. 1, whereby the liquid is sprayed downward and strikes the entire bottom of the biggin. The nozzle has a stem 9 suitable for insertion into the inlet pipe and 40 a packing ring 10 preferably made of cork prevents leakage between the joints and holds the nozzle in the pipe.

The biggin is made of reticulated fabric and has a cylindrical body portion 11 shaped 45 from a single piece of fabric. The bottom 12 has an inwardly turned perimeter 14 sewed about the lower end of the cylindrical body. In order to prevent collapse of the body and to retain its shape a split annular 50 wire member 15 is inserted in a pocket formed in the upper part of a pleat 16. The pocket has open ends 17 so that the member can be slid out of the pocket.

The lower end of the body is also provided

with a pleat 18 formed on the outer side of the 55 wall of the body having a pocket adapted to receive an annular resilient split wire member 19 which tends to expand centrifugally thereby stretching the bottom to keep it flat. The pleat also has open ends 20 to permit 60 withdrawal of the wire member. In this arrangement the wire is covered by the fabric and being located on the other side of the biggin it can readily be removed and it does 65 not come into contact with the liquid. When it is desired to pack, transport or clean the bag both the wire members can be removed. The biggin is supported on a flange 21 projecting from the inside wall of the turn. The nozzle being positioned above the upper 70 end of the bag and on one side thereof permits the bag to be readily placed or removed from the urn. The hot water when it hits the inclined forward part of the nozzle spreads and is sprayed downward toward the bottom 75 part of the biggin and is thoroughly mixed with the ground coffee while the extract slowly trickles through the interstices of the fabric into the boiler.

When it is necessary to reduce or increase 80 the quantity of water issuing from the nozzle it can be slipped from the inlet pipe and another nozzle substituted with more or less perforation depending on the quantity of extract made and the time it is required to 85 brew.

I claim:

1. In a coffee urn the combination with a 90 boiler having a biggin made of fabric with a substantially flat bottom suspended therein, a water inlet pipe located on the upper side of the boiler, and a nozzle mounted on the inlet pipe having a perforated angular outlet positioned on one side of the biggin to spray the water downward so as to strike the 95 entire bottom of the biggin.

2. In a coffee urn the combination with a 100 boiler having a biggin made of fabric with a substantially flat bottom suspended therein, a water inlet pipe located on the upper side of the boiler, and a nozzle removably mounted on the inlet pipe having a right angled perforated outlet to spray the water downward toward the bottom of the biggin.

3. A coffee biggin made of fabric comprising 105 a body and a bottom the body having an upper pleated end for the insertion of a wire ring, and a pleat located at the lower end of

the outer part of the body for receiving a wire member to centrifugally stretch the bottom.

4. A coffee biggin made of fabric comprising a body and a practically flat bottom the body having an upper pleated end for the insertion of a split wire ring, and a pleat ar-

ranged at the lower end of the outer part of the body with a pocket for receiving a split resilient wire ring to centrifugally tension the bottom. 10

In testimony whereof I have hereunto set my hand.

PETER G. ROUSSEAS.
